Primary Examiner — Patricia A Palasik(74) *Attorney, Agent, or Firm* — Banner & Witcoff, Ltd.(57) **CLAIM**

The ornamental design for a machining sample model of machine tools, as shown and described.

DESCRIPTION

FIG. 1 is a front perspective view of a machining sample model of machine tools showing our new design;

FIG. 2 is a rear perspective view thereof;

FIG. 3 is a top view thereof;

FIG. 4 is a front view thereof;

FIG. 5 is a rear view thereof;

FIG. 6 is a right side view thereof;

FIG. 7 is a left side view thereof; and,

FIG. 8 is a bottom view thereof.

The broken line showing of the remainder of the machining sample model of machine tools forms no part of the claimed design.
